(57) CLAIM

The ornamental design for a “playard,” as shown and described.

DESCRIPTION

FIG. 1 is a top, front, and right side perspective view showing our new design for a playard.

FIG. 2 is a top view of the playard shown in FIG. 1.

FIG. 3 is a top, front, and right side perspective view showing an alternate environment view of the playard shown in FIG. 1. FIG. 4 left side view of the playard shown in FIG. 1, the right side view being a mirror image thereof; and,

FIG. 5 is a rear view of the playard shown in FIG. 1, the front view being a mirror image thereof.

The subject matter shown in dashed lines is for illustrative purposes and forms no part of the claimed design.
